Louis A. Marks, Brooklyn, N. Y.

Application July 29, 1952, Serial No. 20,803

Term of patent 3½ years

(Cl. D48—16)

To all whom it may concern:

Be it known that we, Henry Lewis, a citizen of the United States, residing in Rockville Centre, in the county of Nassau and State of New York, and Louis A. Marks, a citizen of the United States, residing in Brooklyn, in the county of Kings and State of New York, have invented a new, original, and ornamental Design for a Lamp Shade, of which the following is a specification, reference being had to the accompanying drawing, forming part thereof.

Fig. 1 is a top plan view of a lamp shade showing our new design;

Fig. 2 is a side elevational view thereof;

Fig. 3 is a fragmentary side elevational view, to a larger scale, showing one of the ornaments.

Fig. 4 is a cross-sectional view taken on the line 4—4 of Fig. 3;

Fig. 5 is a fragmentary side elevational view, to a larger scale, showing another ornament, and

Fig. 6 is a cross sectional view taken on the line 6—6 of Fig. 5.

The characteristic features of our design reside in the portions shown in full lines on the drawing.

We claim:

The ornamental design for a lamp shade, substantially as shown and described.

HENRY LEWIS.
LOUIS A. MARKS.
